UNITED STATES PATENT OFFICE

JULIUS SYLVESTER, OF WASHINGTON, PENNSYLVANIA, ASSIGNEE TO SIMPLEX ENGINEERING COMPANY, OF WASHINGTON, PENNSYLVANIA, A CORPORATION OF DELAWARE

HEATING DEVICE FOR LEERS

Original application filed January 21, 1929, Serial No. 333,887. Divided and this application filed January 4, 1930, Serial No. 418,577.

This invention relates to heating devices for leers, and while primarily designed for the heating of sheet glass annealing leers, may be employed in types of leers, kilns and heating chambers generally; and the present application is a division of my prior application filed January 21, 1929, Serial No. 333,887.

One object of the invention is to provide an improved heating means, preferably of electrical type, whereby the sides of the leer may be heated by heating units separate from those which heat the center of the leer, and also to provide separate heating devices above and below the conveying mechanism, whereby uniform heating of the material under treatment may be secured.

A further object of the invention is to provide means for protecting the heaters below the conveying mechanism from injury or short circuiting by falling particles of broken glass or other material under treatment, and for guiding such broken particles away from the heaters and conducting them to cleanout passages for removal through doors at the sides of the leer.

A still further object of the invention is to provide a leer having zones of varying temperatures, and insulations for said zones differing in degree of heat conductivity for its particular zone.

The invention consists of the features of construction, combination and arrangement of parts, hereinafter fully described and claimed, reference being had to the accompanying drawings, in which:—

Fig. 1 is a diagrammatic side elevation of a sheet glass annealing roller leer to which my improved heating means is shown applied, and a sheet forming apparatus coacting with the roller conveyor of the leer for intermittently forming glass sheets and feeding the same through the leer for annealing treatment.

Fig. 2 is a vertical longitudinal section

through the leer, showing highly heated and less highly heated or relatively cooling sections of the leer.

Fig. 3 is a vertical transverse section on line 3—3 of Fig. 2.

In the illustrated embodiment of my invention as herein disclosed, I have shown the invention embodied in a leer chamber, kiln or tunnel 1 for annealing sheet glass, through which kiln the glass sheets intermittently formed by a casting apparatus 2 is transported by a roller conveyor 3, driven by any preferred type of driving apparatus. The rolls 3 of the conveyor are arranged sufficiently close together to properly support the glass sheets, and the rolls located outside the kiln are journaled in a suitable supporting frame while those located inside the kiln are journaled in the side walls of the kiln, as shown particularly in Fig. 3. The rolls themselves may be of any suitable construction for the purpose, but I preferably employ the types of rolls disclosed in my aforesaid application Serial No. 333,887. The kiln is provided at its inlet end, at least, with suitable doors adapted to be opened as required to permit the sheets to pass into the kiln and then closed to prevent loss of heat from the kiln when glass is not being annealed or no new sheets are being supplied.

Any suitable construction of doors for this purpose may be employed. The kiln, as illustrated in Fig. 1, is made up of two principal divisions which may be referred to as the highly heated portion 19 and the less highly heated portion 20. Each of these portions is made up of a plurality of sections. The characteristics of the highly heated portion are the more expensive construction designed to prevent heat radiation and the closer spacing of the heating units as indicated in Fig. 2, which figure shows the two adjacent sections of the highly heated and cooling portions of the kiln at their point of intersection. The temperature within the

kiln may be regulated as desired, but preferably ranges from a maximum of about 1200° F. at a point near the kiln entrance, to a temperature of about 150° F. at the end of 5 the cooling portion of the kiln. The glass sheets 16 are conveyed by the roller conveyor through the kiln at a proper speed for the annealing action, the sheets being heated to annealing temperature in the highly heated 10 portion of the kiln and then passing to the cooling portion of the kiln, where their temperature is reduced, and the sheets finally discharging at the end of the kiln upon a discharge conveyor from which they may be 15 removed by suitable lifting means.

The means for heating the kiln comprises electric heating units arranged in two groups, 23 and 24, one above and the other below, 20 the conveyor rolls. Thus both the top and bottom of the glass passing over the rolls will receive heat. The lower group of heating units is preferably protected from damage and short circuiting by means of casings enclosing them, which casings include hoods or 25 covers 25 which prevent broken glass or other material being conveyed by the rolls from falling upon the heating coils. The units 24 are closely spaced in the highly heated section of the kiln, and are placed farther apart 30 in the cooling section. Suitable control mechanism, not shown, is provided for regulating the amount of current supplied to the individual units along the length of the kiln in order to ensure the proper supply of 35 current to each heater and the proper lowering of temperature from the entrance end to the discharge end of the kiln. The highly heated portion of the kiln is provided with solid masonry 26 designed to prevent loss of 40 heat, while the cooling section of the kiln has a comparatively thin floor 27, supported on a framework 27'.

Preferably the units of the lower group of heating coils are arranged in three sections 45 28, 29 and 30, arranged, respectively, at one side of the center, at the center, and at the opposite side of the center of the kiln, so that an effective arrangement of heating units is provided allowing them to be individually 50 controlled. This arrangement, clearly shown in Fig. 3, permits the sides of the kiln to receive as high a degree of heat as the center. This ensures evenness of glass annealing and prevents deformation of the rolls. The heaters 23 above the rolls may be arranged solely 55 between the center and the sides of the kiln, the center space being devoid of a heater, as the rising heat, by the described arrangement of the coils, will provide for a uniform heating 60 of the glass or other material above and below the line of the conveyor.

Beneath the rolls 3 are transverse cleanout 65 passages 31, 32, which slope from the center of the kiln downwardly and outwardly to openings at opposite sides of the kiln,

closed by removable doors 34. This permits of the removal of broken glass or other broken particles of material which falls downward between the rolls and is broken casually while in transit. The hoods or covers 25 70 are provided with sloping sides, as clearly shown in Fig. 2, and the heaters and their hoods are so arranged with respect to the cleanout passages as to adapt said sloping sides of the hoods to deflect the falling particles downward into the cleanout passages 75 31, 32, from which they may be readily removed at required intervals.

As shown particularly in Figs. 2 and 3, the passages 31 and 32 are arranged below 80 and in a vertical plane between each pair of transverse heater groups 28, 29 and 30, so as to directly receive the broken glass sliding off the relatively inner sloping sides of the hoods 25 of the heaters of that pair of groups, 85 and said passages 31 and 32 are provided with sloping sides which extend outward and upward laterally beneath the heaters of such pair of groups and intersect the sloping sides 90 of adjacent pairs of channels which lie on opposite sides of the first-named channels and in alignment with the spaces between adjacent pairs of heater groups, the arrangement being such that the intersecting sides of adjacent sets of channels lie in a vertical plane between such adjacent sets of heaters of adjacent pairs, whereby the broken glass particles passing over the relatively inner faces of the hoods of a pair of heaters fall directly into the intervening channels below, while the particles of 95 glass passing over the relatively outer faces of the hoods of a pair of heaters and the relatively outer faces of the hoods of the next adjacent pair or pairs of heaters fall between the heaters of adjacent pairs and down 100 upon the intersecting sides of adjacent sets of channels and are guided thereby into such channels. By this means the necessity of employing channels on opposite sides of each group of heaters and between the same and 110 each group of heaters at opposite sides thereof is avoided, the cost of kiln construction reduced, and greater simplicity of construction and efficiency of operation obtained.

From the foregoing description, it will be 115 seen that my invention provides a simple, reliable and efficient type of heating and insulating means whereby the advantages set forth are gained. While the invention is set forth particularly for use in connection with 120 glass annealing kilns, it will, of course, be understood that it may be employed in conjunction with kilns for action upon other materials and for drying and many other purposes.

Having thus fully described my invention, I claim:—

1. A leer having a heating chamber, a ware conveyor therein comprising transversely arranged longitudinally spaced rolls disposed 125

- between the top and bottom of the chamber, heating means at the top of the chamber and above the rolls comprising longitudinally spaced pairs of unitary electrical heaters, the heaters of each pair being jointly controlled and extending transversely of the leer chamber at opposite sides thereof and spaced from the center of the chamber, and heating means at the bottom of the chamber and below the conveyor comprising longitudinally spaced groups of unitary electrical heaters, each group consisting of three independently controlled heaters extending transversely of the leer chamber and arranged respectively at the center of the leer, between the center and one side of the leer, and between the center and the other side of the leer, whereby the sides of the leer at the top will be directly heated to substantially the same degree and the center and sides of the leer at the bottom may be controllably heated to the same or variable degrees, while the center of the chamber at the top will be heated by rising currents of heat from below. 70
2. A leer having a heating chamber, an openwork conveyor therein disposed between the top and bottom of the chamber, heating means at the top of the chamber and above the conveyor comprising longitudinally spaced pairs of unitary electrical heaters, the heaters of each pair extending transversely of the leer chamber at opposite sides thereof and spaced from the center of the chamber, and heating means at the bottom of the chamber and below the conveyor comprising longitudinally spaced groups of unitary electrical heaters, each group consisting of three independently controlled heaters extending transversely of the leer chamber and arranged respectively at the center of the leer, between the center and one side of the leer, and between the center and the other side of the leer. 75
3. A leer having a heating chamber, a roll conveyor for conducting ware therethrough, a plurality of pairs of longitudinally spaced groups of heaters disposed at the bottom of said chamber, the heaters of each group extending transversely of the chamber, doors at the sides of the chamber, cleanout passages being formed in the base of the chamber and in alinement with the spaces between the groups of heaters of each pair and sloping in opposite directions downwardly toward the doors at the opposite sides of the kiln, each channel having its side walls inclining upwardly and outwardly beneath the related pair of heater groups and intersecting the adjacent side walls of the channels associated with other heater groups at opposite sides thereof at points below and between the heater groups of adjacent pairs, and protective hoods overlying the groups of heaters and having inner and outer sloping sides, the relatively inner sloping sides of the hoods of the 80 85 90 95 100 105 110 115 120 125 130
- heaters of a pair being arranged to discharge broken particles of glass directly into the channels between said pairs and the relatively outer sloping sides of the hoods of such pair of heaters and of adjacent pair or pairs of heaters being arranged to discharge particles of broken glass downwardly onto the intersecting portions of the sloping sides of the channels between the pairs of heaters for passage to said channels. 80
- In testimony whereof I affix my signature. JULIUS SYLVESTER. 85
